FOREIGN PATENT DOCUMENTS

RU 96310 12/2015

Primary Examiner — Kevin K Rudzinski*Assistant Examiner* — Kimberly Barnes(74) *Attorney, Agent, or Firm* — Abel Schillinger, LLP;
Thomas H. Osborn(57) **CLAIM**

The ornamental design for a shingle, as shown and described.

DESCRIPTION

FIG. 1 is a right side elevation view of a shingle showing our new design, the left side elevation view being a mirror image of the right side elevation view;

FIG. 2 is a front elevation view thereof; and,

FIG. 3 is a front elevation view of another embodiment of a shingle and the right and left side elevation views are the same as the shingle of FIG. 1.
